PROCESS OF CRACKING OR OTHERWISE ALTERING THE COMPOSITION OF HYDROCARBONS

Filed May 3, 1915

Attorneys

UNITED STATES PATENT OFFICE.

AUGUSTÉ J. PARIS, JR., OF BRADFORD, PENNSYLVANIA.

PROCESS OF CRACKING OR OTHERWISE ALTERING THE COMPOSITION OF HYDRO-CARBONS.

Application filed May 3, 1915. Serial No. 25,402.

This invention is a process of cracking, or otherwise altering the composition of, hydrocarbons, and the salient feature of the invention consists in compressing the material under treatment in such manner that sufficient heat is produced to cause the desired change in such material.

Heretofore, in compressing gases, it has been the aim, as far as possible, to endeavor to prevent an elevation of temperature in the compression cylinder. In the present process, in contradistinction, I aim to secure such a high temperature in the compression cylinder as will effect the cracking, or other change, in the gas or vapor under treatment.

Moreover, instead of relying entirely on the heat produced by the compressing operation, the material may be pre-heated, prior to its introduction into the compression cylinder, or the compression cylinder may be jacketed, as is usual, but, instead of introducing a cooling medium therein, the gas, vapor, or liquid may be allowed to flow therethrough prior to its introduction into the compression cylinder, whereby it is preliminarily heated. Furthermore, both of the methods for preliminarily heating the material referred to may be employed in conjunction, if desired.

The process is particularly adapted to the treatment of petroleum, or its distillates, coal or analogous oils, for the purpose of making motor spirits or similar products, resulting from the cracking or polymerization of the oil. In practically carrying out the process, the system in which the compression is effected is normally supplied with gas of suitable character, such as natural gas, coal gas, water gas, marsh gas, which serves as a vehicle or carrier for the oil.

Features of the process, other than those described, will appear from the hereinafter detailed description, and, moreover, will readily suggest themselves to those skilled in the art.

In the accompanying drawings, I have shown one form of apparatus, which also is part of the present invention, wherein the process under consideration may be practiced, but it will be understood that this apparatus is illustrative, only, and that the process may be carried out in various other forms of apparatus.

Figure 1 shows diagrammatically, partly

in section and partly in elevation, a complete apparatus;

Figure 2 shows a modified form of compressor, wherein provision is made for circulating the gas, liquid or vapor through the jacket of the compression cylinder prior to its introduction into the cylinder, and

Figure 3 is a vertical section of one of the separators shown in Fig. 1, e. g., E.

Referring to the drawings, A is an oil tank containing oil *a*, and B is an oil pump for pumping the oil from tank A into compression cylinder C. The oil outlet *b* from pump B leads to a main *b'*, connecting with which are a riser *b*², branch *b*³, and valve *b*⁴, through which oil is introduced into compression cylinder C through its oil inlet *b*⁷. If desired, instead of passing the oil through branch pipe *b*³ directly into compression cylinder C, it may be caused to pass through pre-heater D, coil *d* of which connects with riser *b*² through valve *b*⁵, the outlet of the coil connecting, through valve *b*⁶, with the inlet to compressor C. Coil *d* is preferably contained in a bath *d*² of suitable liquid, such as oil or water, or said coil may be heated by steam; the aim being to avoid direct heating of the oil and thus preclude any preliminary cracking of the oil.

As shown, the casing of pre-heater D is provided with an inlet *d*³ and outlet *d*⁴, for the introduction and exit of the heating agent. In the specific form shown, pre-heater D receives its heat from a gas or other suitable burner *d*⁴.

The outlet pipe *c* from cylinder C leads to a separator E, in which samples of the heaviest condensable oils accumulate. They may be drawn off for testing or other purposes through cock *l*. Pipe *c* may be provided with a valve *c*^a, whereby in addition to the means shown, a further expedient is provided for regulating the pressure under which compressor C pumps. A pipe *l'*, provided with a valve *l*², extends from separator E and leads through valve *l*³ to separator E'.

The outlet *c'* from separator E leads to a large separator E', in which are separated the heavier portions of the treated product, which accumulate therein as shown at *c*².

The outlet *c*² from separator E' leads to a further separator E², in which a further separation of the heavy products takes place. Outlet *c*⁴ from separator E² connects with a

condenser F through valve g , wherein all the condensable hydrocarbons are condensed from the gas, whence they flow through pipe c^5 into separator E³, and may be drawn off through valve c^6 .

- The gas under treatment, escaping through gas outlet c^7 from separator E³, enters riser c^8 , whence it may pass into the expansion cylinder G through inlet c^9 , where it does 10 work by virtue of its expansion, and the power generated may be used for any purpose desired. The main purpose of expanding the gas at this stage is, however, to so reduce its temperature that it may be used 15 for cooling condenser F. The expanded gases pass from cylinder G through separators or traps E⁴ E⁵, in which any residual condensable oils are separated, as well as the lubricant which has been used in the expansion cylinder G. The gas, escaping from 20 separator E⁵, enters the cooling chamber f, of condenser F, through inlet f¹, and passes off through pipe f², whence it passes through down-take f³, branch f⁴, into coil d⁵ of pre-heater D², wherein it becomes reheated and 25 enters compression cylinder C through the valve-controlled gas inlet f⁵ thereof. Pre-heater D² may be heated by a gas burner k, or other suitable means, corresponding to 30 burner d⁴ of pre-heater D.

Instead of feeding the oil from pump B through pre-heater D, or pipe b³ into cylinder C, as heretofore described, the valve g in pipe b¹ may be closed, thereby shutting off communication with riser b². Valve g' 35 may then be opened, and the oil from pump B allowed to pass through riser g², into inlet f⁴ of coil d⁵. The oil may thus be commingled with the expanded gas which comes 40 from condenser F through pipe f⁸ and enters coil d⁵, thereby enabling the mixed oil and gas to be introduced into compressor C through inlet f⁵.

If desired, the expanded gas from cylinder G, after passing through separator E⁴, may be caused to enter down-take h, branch h', and, after passing through separator E⁵, wherein any residual condensable oils are 45 separated, enters riser h², thence through pipe f⁶, directly into compressor C, thereby dispensing with the passing of the gas through condenser F and pre-heater D². Instead of passing the gases through pipes h, h', h² and f⁵, directly from expansion cylinder G into compressor C, as just described, the valve h³ of riser h² may be closed, and said 50 gases passed through riser h⁴, having a valve h⁵, through valve h⁶ into inlet f⁴ and pre-heating coil d⁵, thence through inlet f⁵ to compressor C.

Instead of passing the gases which flow through pipe c⁴ from separator E² into condenser F, as described, they may be caused to flow from pipe c⁴ into down-take c¹⁰ into 65 inlet c⁹ of expansion cylinder G. The gases,

having been expanded in cylinder G, will then be led, as described, to compressor C, either directly through pipes h, h', h², or through pipes h, h', h⁴ and pre-heater coil d⁵ to said compressor.

If it is desired to allow the gas from separator E² to escape from the system, this may be done by manipulating proper valves so as to cause the gas to escape into the atmosphere through outlet c¹¹ of pipe c⁴. Moreover, the expanded gas from condenser F, after entering pipe f², may, if desired, be allowed to enter riser f⁴ and escape through pipe n into the atmosphere. The gas employed in the system may be introduced into compressor C through inlet h⁷ of riser h², through compressor inlet f⁵.

Referring to Figure 2, a compressor C' is shown as being provided with an oil heating jacket C². The oil inlet to the jacket is shown at i¹, and the oil, after circulating in the jacket C², enters the compression cylinder through port i². The inlet for the gas is shown at i³ and the outlet for the compressed products at i⁴, said pipe i⁴ corresponding to the pipe c of compressor C, and, in practice, will lead to the separator E'. If desired, for any special reason, the heating jacket C² may be used as a cooling jacket.

If desired, at least for temporary use, oil tank A and pump B may be shut off from the system by closing valve j. The oil to be treated may be confined in separating tank E', and the normal pressure in the system may be used to force the oil therefrom into compressor C, either directly through pipes b² b³ and oil inlet b⁷, or indirectly through pre-heater D. The oil might also be introduced into compressor C by suction.

The system is provided with numerous manually operated valves, the function of which will be manifest, as well as the customary gages, thermometers, and relief valves, none of which need be described in detail.

Having described the construction of the apparatus, its mode of operation will be clear, but it may be summarized as follows, assuming the material under treatment is petroleum, or its distillates.

Assuming it is desired to crack or polymerize petroleum oil, or one or more of the fractions thereof, the oil is introduced into compression cylinder C in one of the several ways described, namely, directly through pipes b, b², b³, valve b⁴ and cylinder oil inlet b⁷, or indirectly through pre-heater D or pre-heater D², it being, in this latter case, mixed with gas prior to its introduction into the compression cylinder C. In the event the oil, per se, is introduced into the cylinder C through oil inlet b⁷, it meets the gas therein introduced through inlet f⁵. A mixture of oil and gas having been obtained

in cylinder C, the same is compressed to such a degree of pressure that the resulting heat, or elevation of temperature, cracks, or partially cracks, the oil. The resulting mixture is then treated as described to effect the desired separation of the light and heavy products.

In practicing the separating process, one of the several alternative methods described 10 may be employed.

It is not deemed necessary to specify the specific pressures or temperatures required to effect the results desired, since these vary with the particular oil or other material 15 treated and are well known to those skilled in the art. However, a specific illustration of the mixture of oil and gas which may be used, as well as the temperature and pressure employed, may be mentioned in the following; natural gas may be saturated with the fuel oil distillate of Pennsylvania fuel oil, say of 38 degrees Baumé. In practice, about 12 lbs. of such oil is sufficient to saturate about 50 lbs. of the gas, though more or 20 less oil may be used. This mixture may be preheated to 150 degrees F. before compressing it, whereupon it is compressed to a pressure of 500 lbs. This results in a temperature of upwards of 900 degrees F., a 25 which is amply sufficient to crack the oil vapors. If the mixture of oil and gas is initially preheated above 150 degrees F., a lower pressure may be employed than that specified. Moreover, if the mixture of oil 30 and gas is subjected to an initial or preliminary pressure, which raises it to a temperature of about 400 degrees F., it may then be introduced into the compression cylinder and further compressed to about 600 lbs. 35 pressure, which will result in a temperature more than sufficient to crack or otherwise alter the oil vapors. The temperature of preheating is determined by the quantity of oil to be treated at each stroke, and also by 40 the gas pressure at the intake of the compressing cylinder. If the intake is above atmospheric pressure, then the gas should be preheated to a point above the theoretical temperature corresponding to such pressure 45 if the cracking process is to be carried out at the lowest pressure possible in the compressing cylinder. Pressure on the oil does not produce heat, so such oil must abstract 50 heat from the gas; accordingly, allowance must be made to produce the required elevated temperature of the oil, and the theoretical amount of heat due to compression 55 of the gas would not be indicated by a thermometer, as the oil would, as stated, absorb some of the heat resulting from the compression of the gas.

It will be understood that, in general, the gas or aeriform fluid introduced in compression cylinder C serves, mainly, as a carrier or vehicle for the oil or other liquid or liq-

uids operated upon. In other words, it takes up the liquid in the form of a spray, vapor, or mist, since, manifestly, the liquid, as such, could not be compressed. Any loss of gas from the system by leakage, or otherwise, may be replaced as desired.

The processes, outlined, especially in details, may be varied without departing from the spirit of the invention, and may be modified, generally, to meet particular conditions 75 of operation.

Having thus fully described the invention, what I claim as new, and desire to secure by Letters Patent is:

1. The process of altering the boiling 80 points of hydrocarbon oils, which consists in heating the hydrocarbon oil to a temperature below its boiling point, mixing the oil without the separation of vapors therefrom with a gas, introducing the said mixture into a compressor, compressing said mixture for the purpose of heating the mixture, and subsequently cooling the resultant products and separating the liquids from the 85 gas.

2. The process of altering the boiling 90 points of hydrocarbon oils, which consists in mixing the oil with a gas, heating the mixture to a temperature below the boiling point of the oil, introducing such mixture containing the entire contents of the oil into a compressor, compressing the mixture thereby heating the mixture, and subsequently cooling the resultant products and separating the liquid from the gas.

3. The process of altering the boiling 95 points of hydrocarbon oils, which consists in introducing a heated mixture of hydrocarbon oils and a gas, at a temperature below the boiling point of the oil, into a compression cylinder, and subjecting the mixture in the cylinder to a pressure sufficient to crack 100 the oils.

4. The process of altering the boiling 105 points of hydrocarbon oils, which consists in mixing the liquid petroleum in a finely divided state with a gas, compressing the mixture under such conditions as to cause the desired change and subsequently cooling the resultant products.

5. The process of altering the boiling 110 points of hydrocarbon oils, which consists in mixing the liquid hydrocarbon oils with a gas, compressing the mixture and heating it thereby under such conditions as to cause the change desired, and cooling the resultant products.

6. The process of altering the boiling 115 points of hydrocarbon oils, which consists in mixing the liquid petroleum with a heated gas at a temperature below the boiling point of the petroleum, compressing the mixture under such conditions as to cause the change desired, and cooling the mixture.

7. The process of altering the boiling 120

- points of hydrocarbon oils, which consists in heating the oil at a temperature below its boiling point, mixing it with a gas, compressing the resultant mixture under such conditions as to cause the change desired, and cooling the resultant products.
8. The process of altering the boiling points of hydrocarbon oils, which consists in heating without distilling a hydrocarbon oil without altering its specific gravity, mixing the oil with a heated gas, compressing the resultant mixture under such conditions as to cause the change desired, and cooling the resultant products.
10. The process of producing hydrocarbon oils having low boiling points from hydrocarbon oils having high boiling points which consists in preheating the oil to be treated and subjecting the oil so treated in the presence of a vapor to a pressure sufficient to heat and compress the same to the temperature and pressure of conversion, and cooling the resultant products under reduced pressure.
12. The process of producing hydrocarbon oils having low boiling points from hydrocarbon oils having high boiling points which consists in preheating at least a part of the material to be treated in one container, adding a vapor or gas thereto, passing the material so treated including the vapor or gas into a second container and subjecting the material within said second container to a pressure sufficient to heat and compress the same to the temperature and pressure of conversion, and cooling the resulting products under reduced pressure.
14. The process of producing hydrocarbon oils having low boiling points from hydrocarbon oils having high boiling points which consists in passing the oil under pressure through a heating device, passing the oil into a compression chamber, subjecting the oil in said compression chamber to a pressure sufficient to heat and compress the same to the temperature and pressure of conversion, and passing the oil into another container wherein it is retained under said pressure, without being subjected to cooling in said other container.
16. The process of producing hydrocarbon oils having low boiling points from hydrocarbon oils having high boiling points which consists in passing the oil under pressure through a heating device, passing the oil into a compression chamber, subjecting the oil in said compression chamber to a pressure sufficient to heat and compress the same to the temperature and pressure of conversion, and passing the oil into another container wherein it is retained under said pressure, without being subjected to cooling in said other container.
18. The process of producing hydrocarbon oils having low boiling points from hydrocarbon oils having high boiling points which consists in passing the oil under pressure through a heating device, passing the oil into a compression chamber, subjecting the oil in said compression chamber to a pressure sufficient to heat and compress the same to the temperature and pressure of conversion, and passing the oil into another container wherein it is retained under said pressure, without being subjected to cooling in said other container.
20. The process of producing hydrocarbon oils having low boiling points from hydrocarbon oils having high boiling points which consists in subjecting the oil to be treated to the action of heat at a temperature below its boiling point, mixing it with a gas and subjecting the mixture to a pressure sufficient to heat and compress the same to the temperature and pressure of conversion, without application of heat to the exterior of the container in which said pressure is applied to said mixture, and cooling the resulting products under reduced pressure.
22. The process of producing hydrocarbon oils having low boiling points from hydrocarbon oils having high boiling points which consists in passing liquid oil under pressure through a heating device wherein said oil is heated at temperatures below its boiling point, mixing a gas with said oil, and passing the mixture into a second container and subjecting the mixture within said second container to a pressure sufficient to heat and compress the same to the temperature and pressure of conversion.
24. The process of producing hydrocarbon oils having low boiling points from hydro-

carbon oils having high boiling points, which consists in passing the oil under pressure through a heating device wherein it is heated to a temperature below its boiling point, mixing a gas with said oil, subjecting the mixture to a pressure sufficient to heat and compress the same to the temperature and pressure of conversion, passing the mixture so treated to another chamber and retaining said mixture in said chamber under 10 said pressure, condensing and separating the condensate from the gas.

In testimony whereof I have signed my name to this specification.

AUGUSTÉ J. PARIS, JR.
